UNITED STATES PATENT OFFICE

MAX OERTZ, OF HAMBURG, GERMANY; ANNA EMILIA OERTZ, ADMINISTRATRIX OF
SAID MAX OERTZ, DECEASED, ASSIGNOR, BY MESNE ASSIGNMENTS, TO ANNA EMILIA
OERTZ, OF HAMBURG, GERMANY

HOLLOW RUDDER FOR SHIPS

Application filed April 8, 1929, Serial No. 353,538, and in Germany March 1, 1929.

In streamline rudders, which are constructed as hollow bodies, and which, in general, have a pivot at top and bottom only, the mounting and dismounting of the rudder entails difficulties which hitherto could only be overcome by introducing certain disadvantages in the construction of the rudder. Thus, for example, in balanced streamline rudders which are pivoted to a pillar connecting the upper part of the stern post to the sole piece of the stern frame the rudder blade has to be opened up along its whole height after the rudder shaft has been disconnected. Such a method of construction has, however, the great disadvantage that all the detachable strips of plating can only be fixed in place with screws which latter cannot be secured by welding over their heads, as otherwise dismounting would be impossible without considerable trouble. Now experience shows that these rivet screws may very easily work loose, owing to the vibration set up in the screw race and hence the rigidity of the rudder blade may be seriously impaired, especially as the seat of the insecurity is located just in the region of the greatest bending stress on the rudder. Apart from the fact that a rudder of this kind can only be kept watertight in its after part, the screwing in and out of the rivet screws entails considerable labour, especially if they have become rusted in after a long voyage.

It is an object of the present invention to provide a hollow streamline rudder of novel and improved construction such that the rigidity of the rudder in all its parts is completely assured, notwithstanding the fact that provision is made for easily and quickly mounting and dismounting such rudder.

According to one practical embodiment of the invention the gudgeon pins or pintles about which the rudder rotates, can be moved in upward and downward directions respectively after the cotters which hold them in position have been knocked out. After the rudder shaft has been disconnected the rudder blade can then at once be removed rearwardly or sideways. The socket bearings on which the rudder blade turns are sunk into the corresponding cast steel parts which

bound the rudder above and below, in such a way that no reduction of strength in the rudder body and, in general, no diminution of the desired degree of water-tightness can take place. The liners of the bearings, which when the rudder was constructed with the pillar herein first mentioned, had to be made in halves, can now be made in one piece, which, of course materially strengthens it.

In the accompanying drawings:

Figure 1 shows in section a constructional form in which the supporting pintle *f* which has to take the weight of the rudder, is arranged at the bottom and wherein, therefore, the cotter *k* which holds the pintle and also the casting *b* are kept correspondingly strong. If the rudder be worked in a water-tight condition, as in most cases it will be, the supporting pintle *f* will be relieved of end thrust by the upward thrust of the rudder blade.

Figure 2 shows a practical constructional form in longitudinal section and

Figure 3 the same in transverse section both sections being drawn to an enlarged scale and taken on the line X—X of Figure 1.

Figures 4 and 5 are views similar, respectively to Figures 2 and 3 and show the construction of the lower pintle. Here also the sections are taken on the line X—X of Figure 1 and the figures drawn to an enlarged scale. Figures 3 and 5, in particular, show the manner in which the cotters secure the pintles.

Figure 6 shows diagrammatically an example of a cross sectional form of rudder blade.

The rudder body *a* is bounded at the top and bottom by cast steel members *b* in which are inserted the liners of the socket bearings for the pintles *f* which, in their turn, are held in place by the cotters *k*. It will be seen that when these cotters have been withdrawn, the pintles can be easily removed in upward and downward directions respectively (conveniently with the help of the eye *d*) and the rudder is then free to be unshipped after the rudder shaft *m* has been disconnected from the rudder body *a*. The mounting of the rudder is effected by carrying out exactly the same operations in reverse order.

Figures 7 to 15 in which the same reference letters are employed for like parts, show a form of construction in which the supporting pintle is arranged in the upper half of the rudder.

Figure 7 shows a section of this constructional form which will be understood without further explanation.

Figure 8 is an enlarged section on the line X—X of Figure 7.

Figure 9 is a transverse section on the line X—X of Figure 7 at the part where the supporting gudgeon and pintle are located.

Figures 10 and 11 show longitudinal and transverse sections, respectively, through the lower part of the rudder, on an enlarged scale.

Figure 12 shows a tool with the aid of which the pintle can easily be started from its conical seating. After removing the cotter 20 *h* and inserting this tool a blow is delivered thereon in the direction indicated by the arrow, the pintle being thereby unseated, so that it can easily be drawn out, say by a pull on the eye *d*.

Figure 13 shows an example of a cross section for this form of rudder.

Figures 14 to 17 show the second form of construction in accordance with the invention. Here the pintles are not removable 30 but the parts of the rudder which are intended for the reception of the pintles are each provided with a bearing one half of which is removable.

Figure 14 is a longitudinal section, and

Figures 15 and 17 are sections on the line X—X of the upper and lower sides respectively, these sections being drawn to a larger scale.

Figure 16 shows, also on an enlarged scale, 40 a horizontal section on the line A—B of Figure 14.

The rudder body *a* is bounded at the top and bottom by cast steel members *b* in each of which the half *p* of the bearing through 45 which the bolts *q* can be screwed is fitted. In the case illustrated a thrust ring *r* is provided to take the weight of the rudder but this ring may be dispensed with if the usual type of pintle with a thrust pan as shown in Figure 4 be employed. In like manner a thrust ring may obviously also be provided instead of using the supporting pintles shown in Figures 1 to 13. The holes round the nuts and heads of the bolts *q* may, if necessary, be 55 filled in with cement so as to obtain a smooth surface on the rudder.

In the present specification constructional examples are shown and described for balanced rudders only but it is to be understood 60 that the invention is not limited in its application either to balanced rudders or to rudders of streamline contour. The invention is applicable to all hollow rudders and thus also to rudder structures made in two parts, for instance, to the Oertz rudder and to other

hollow rudders. Further, it is obviously within the scope of the present invention to employ one of the constructional forms herein described at the top of the rudder and the other constructional form at the bottom end thereof. 70

What I claim is:—

1. In a dismountable ship's rudder assembly, a rudder comprising upper and lower stiffening members each with a pintle receiving cavity and fixed rudder plating extending between said members, a stern frame with pintle holding gudgeons, removable pintles adapted to penetrate the gudgeons and the pintle receiving cavities and means for locking 80 the pintles in the gudgeons. 75

2. In a dismountable ship's rudder assembly, a hollow watertight rudder structure comprising upper and lower stiffening members each with a pintle receiving cavity and fixed plating extending between said members to enclose therewith the hollow watertight space, a stern frame with pintle holding gudgeons, removable pintles adapted to penetrate the gudgeons and the pintle receiving cavities and means for locking the pintles in the gudgeons. 85 90

3. A ship's rudder comprising a hollow body, the top and bottom walls of the hollow body having a certain thickening or stiffening portion, outwardly opening recesses in said thickened portions, finger bolts detachably secured in said recesses for connecting said rudder directly to the rudder stem, said detachable finger bolt connections in the recesses in the top and bottom walls of the body of the rudder, while being disposed within the sphere of the hollow rudder body, are readily accessible for attachment and detachment independently of the plating of the rudder. 95 100

4. A hollow rudder according to claim 3 and so constructed as to shut off watertight the said finger bolt connections from the interior of the hollow rudder body. 110

5. In combination with a hollow rudder according to claim 3, said finger bolts, when the rudder is mounted, being removable from the rudder and from the rudder stem, the lower bolt downwardly, the upper bolt upwardly, said finger bolts having a lateral opening, and a key for cooperating with said opening to retain the bolts in operative position in the stem, said key being removed to remove the bolts. 115 120

Signed at Hamburg, Germany, this 26th day of March, 1929.

MAX OERTZ.
